CLAIM

The ornamental design for a coffee table, as shown and described.

DESCRIPTION

FIG. 1 is a top perspective view of a coffee table;
FIG. 2 is a top view of the coffee table;
FIG. 3 is a bottom view of the coffee table;
FIG. 4 is a left side view of the coffee table;
FIG. 5 is a right side view of the coffee table;
FIG. 6 is a front elevational view of the coffee table; and,
FIG. 7 is a rear elevational view of the coffee table.
The broken lines in the drawings depict portions of the coffee table and form no part of the claim.

1 Claim, 5 Drawing Sheets
